COMBINATION STEP BLOCK

Gouverneur Cadwallader, Solebury, Pa.

Application September 23, 1952, Serial No. 311,096

1 Claim. (Cl. 90—59)

The present invention relates to set-up appliances for machine shop work and more particularly to an improved combination step block.

In step blocks heretofore used in association with a clamp for holding a work piece fast to a table for a machining operation, trouble is constantly occurring due to slippage of the clamp upon the plane level treads of the blocks and as a result end movement of the clamp, due to vibration, so changes the set-up relation as to cause inaccurate machining. Such endwise movement is difficult to notice until some damage occurs to the work piece.

An object of the invention is to provide an improved step block for machine shop set-up operations.

Another object is to provide a combination step block, packing block, and V-block.

Another object is to provide a step block wherein an associated clamp is rigidly held against displacement during a machining operation.

Another object is to provide a step block wherein a wide range of levels is possible, any one of which can be selected to match the height of a work piece for accurate machining.

A further object is to provide a step block for association with a clamp for three point support, of which one point seats upon the block.

A still further object is to provide a step block having inclined treads respectively for coaction with an overlying hook-like end of a clamp.

A still further object is to provide a step block wherein means are incorporated for mounting the step block upon rollers.

Further objects will hereinafter appear.

In the accompanying drawings, Fig. 1 represents a side elevation of a combination step block embodying one form of the present invention; Fig. 2 represents a front elevation of the same; Fig. 3 represents a plan of the same; Fig. 4 represents a side elevation of the block as set up for holding a work piece by means of a clamp having a gripping jaw with which the step block of the invention is specifically shaped for association therewith; Fig. 5 represents a section on line 5—5 of Fig. 4; Fig. 6 represents a side elevation of a modified form of the invention; and Fig. 7 represents a front elevation of the block of Fig. 6.

Referring to the drawings and more particularly to Figs. 1 to 5, the block is shown as generally of triangular form having two faces 10 and 11 at right angles but interconnected at an approximate forty-five degree angle by a plurality of steps formed respectively by treads 12 and risers 13 in the position of the block shown in Fig. 1, as supported by the face 10. It will be understood that the treads 12 become risers and the risers 13 become treads when the block is turned to seat upon the face 11. The present description will follow the position shown in Fig. 1. It will be observed that the face 10 is longer than the face 11; illustratively, the former may be three inches and the latter two and one-half inches for selective heights according to which is used as the base face.

In the present instance there are five equally spaced

2

steps formed by treads 12 and risers 13, of which the risers 13 are shorter than the treads 12, each by a predetermined equal amount, to thereby provide one series of supporting levels in one position of the block and a different series of supporting levels in the other position of the block. Thus, when the treads 12 are used as shown in Fig. 1, the short risers 13 respectively define vertical levels for accurate selective alignment with the top of a work piece 14 to be held by a horizontally disposed clamp 15.

10 When the block is turned to seat upon the face 11, then the risers 13 become treads, so that a series of higher levels are available for selective alignment with the top of the work piece. In this way very accurate adjustments can be made for precise level matching association with a work piece.

As a means for preventing the jaw of a cooperating clamp from riding off of a step tread due to vibration initiated by a tool operating upon the work piece, the treads 12 are each rearwardly inclined at angle preferably between two and five degrees to the horizontal so that the outer meeting edge of the tread with the riser of the next step is at a higher level than its inner meeting edge with the next adjacent riser. The same angular inclination is provided for the risers 13, which, when turned, become treads for the new position of the block. Thus, under both positions of the block the stepped treads form rearwardly inclined surfaces disposed to resist outward movement of the jaw of the clamp 15, when in operative position as shown in Fig. 4. The jaw 16 of the clamp 15 is formed by a concavity 17 in the bottom of the clamp which terminates in a transverse convex end 18 as the jaw proper. This jaw construction functions as a hook overlying the high edge of the tread to seat back of such edge at a lower level. It should be noted (see Fig. 5) that the convex jaw forms a one point support at the block to coact with a two point support at the work piece end of the clamp. Thus, a true three point support is provided and held in place by the T bolt 19 riding in the like slot of the work table 20. As so assembled, endwise displacement of the clamp 15 becomes impossible.

In order that the block of the invention can be used as a packing block, it has parallel sides 21 and 22 spaced to provide a given uniform thickness of selected dimension. Illustratively, the block may have a thickness of one inch. Also, it is preferable to provide a through opening 23 to reduce the weight without affecting its efficiency.

For the purpose of using the block as a V-block, that is one capable of seating upon cylindrical rollers, one side thereof is provided with a V groove 24, extending, except where interrupted by the through opening 23, from one step to and across the face 10. Also, this same side is provided with a V groove 25 at right angles to the groove 24 and extending, except where interrupted by the through opening 23, from one step to and across the face 11. Thus, either groove can be used to seat upon a roller according to the result desired. Preferably one groove is of different width than the other for selective seating upon rollers of different diameters. As illustratively shown, the groove 24 is shown for a one-half inch roller, and the groove 25 for a three-eighths inch roller, but these dimensions are subject to variation, as will be understood.

In the form of the invention shown in Figs. 6 and 7 provision is made to take care of extra high work pieces and therefore the block is of elongated rectangular shape with the same stepped formation at one end as heretofore described for Fig. 1 and which is designated by the same reference numbers for the treads and risers so that repetition seems unnecessary. In this form the block is illustratively four and one-half inches wide and eighteen inches long and has two transverse through alined openings 26 and 27 for lightness. The face 28 of the block is provided with two transverse V-grooves 29 and 30, the

former being interrupted by the hole 26, and the latter by the hole 27, and the spacing being such as to seat the block upon cylindrical rollers in a level position. Likewise, the opposite block face 31 is provided with two V-grooves 32 and 33, the former being interrupted by the hole 26 and the latter by the hole 27, and the spacing being such as to seat the block upon cylindrical rollers in a level position. Preferably the grooves 32 and 33 are respectively out of alinement with the grooves 29 and 30.

It will now be apparent that a complete unitary combination step block has been devised for work piece set-up whereby a plurality of block positions can be selected according to the particular use, and in each position function efficiently for that use. As a step block it provides two series of steps differently dimensioned to furnish a plurality of set-up positions to thereby give accurate level matching with a work piece. Thus, in one position of the block one series of steps provide a plurality of levels for selection, and in a second position provide a different plurality of levels for selection.

As a packing or work-supporting block, the uniform thickness of the block, when laid upon its side, forms a stable support for a work piece with proper spacing of the latter from a work table.

As a V-block, the block also forms a spacing support between a work piece and a work table, but in this use the V-groove or grooves seat upon a roller or rollers and

thus support the work piece so that by releasing the clamp the block and work piece can be readily shifted to a new machining position. This is of considerable importance where heavy work pieces have to be shifted while maintaining proper relation of associated parts. Also, the raised position of the work piece permits machining to the bottom of the work piece without interference with the table.

Having thus described my invention, I claim:

10 A step block comprising a body in the form of a right prism having two parallel ends right angular intersecting faces and a third face joining said intersecting faces, one of said intersecting faces constituting the base of said body, said third face comprising treads of one width and risers of second width formed step like, the intersection of said treads and risers forming an acute angle.
